ROY H. CHARLTON, OF BELMONT, MASSACHUSETTS, ASSIGNOR TO FILING EQUIPMENT BUREAU, INCORPORATED, OF BOSTON, MASSACHUSETTS, A CORPORATION OF MASSACHUSETTS

FOLDER

Application filed December 2, 1926. Serial No. 152,183.

This invention relates to folders or file wrappers for holding papers or other indexed material in a so-called vertical filing system in which a plurality of folders are grouped in 5 a tray or drawer of a filing cabinet. The present application is a continuation in part of my pending application for file wrappers, Serial No. 120,954, filed July 7, 1926.

A principal feature of the invention is the 10 provision of novel means for reinforcing the upper edge of one leaf of the folder to provide a relatively stiff and stout margin which is adapted to resist the bending stresses and wear to which the folder is subjected by normal handling during use, and to provide a 15 stout and permanent margin or tab for receiving identifying indicia relating to the particular subject matter of the indexed material within the folder.

20 For this purpose I provide a folder which may be of relatively thin and lightweight material and a separate reinforcing strip, preferably of the same material as the folder, which embraces and is adhesively secured to 25 both faces of the rear leaf of the folder over its upper edge. A folder so constructed, having a stiffened upper edge providing a three-ply composite structure, substantially three times the thickness of the sheet material of 30 which it is composed, is extremely durable and wear-resisting in use, yet is inexpensive to manufacture and does not appreciably increase the bulk thickness of the filing system.

An additional advantage of the reinforcing 35 strip hereinafter described resides in the form of the reinforcement and the manner in which it is applied to the folder. In order to prevent the formation of a too pronounced line of weakness at the lower edge of the reinforcing strip, where the folder leaf would tend 40 to break or crack, and to distribute the strain caused by tipping or bending the reinforced edge, one flap of the reinforcement extends a little farther down on the folder than the 45 opposed flap. The tendency of the folder to bend or break along a defined line when the tab is pulled forwardly or backwardly is thus diminished. The wider or deeper flap of the reinforcement is preferably on the rear side 50 of the folder leaf.

Another object of the invention contemplates the use of materials of contrasting color for the body of the folder and the reinforcing strip, respectively, whereby various color combinations may be employed as signals to 55 classify the subject matter within the folders. Although the identifying colors may for some purposes be employed solely upon the edge reinforcement, it has been found that relatively few individual colors may be readily 60 applied to the manila paper of which the folders are usually and preferably constructed. For this reason it is recommended that both the folder and the reinforcement be distinguished by colors of contrasting hue, 65 if greater diversification of possible color signals be desired than can be obtained by available colors for the reinforcement alone.

A preferred embodiment of the invention is shown for the purpose of illustration in the 70 accompanying drawings, in which:

Fig. 1 is a face view of a folder having the improved features set forth above, one corner of the front leaf of the folder being turned outwardly; and

Figs. 2 and 3 are enlarged sections through the rear leaf of the folder on the lines 2-2 and 3-3, respectively, of Fig. 1.

The folder may be made of any suitable flexible sheet material having the necessary 80 stiffness, such for example as stout manila paper, and consists of a front leaf 4 and rear leaf 5 folded thereon along the bottom edge 6. The upper edge 7 of the front leaf preferably terminates a short distance below the normal 85 upper edge 8 of leaf 5, but these edges may register or may be spaced apart more or less, as desired. An integral tab 9, having an upper edge 10 parallel to edge 8, preferably projects above the normal upper edge of the 90 rear leaf.

A reinforcement is adhesively secured to both faces of the tab 9 and upper margin of the rear leaf 5 along the entire width of the folder, providing a stiffened edge having approximately three times the thickness of the leaf. The reinforcement may be of the same material as the folder and preferably consists of a single strip folded at 11 over the tab edge 10 and having a front flap 12 and rear flap 13 100

which may be pasted or glued to the respective faces of the tab and leaf margin. For the reasons heretofore explained, the rear flap preferably extends downwardly on leaf 5 a short distance farther than the front flap so that the respective lower flap edges 14 and 15 do not register with each other but are located at different levels on leaf 5.

The reinforcing strip may be prepared and applied to the folder in any convenient way; for example, a strip may be folded over a straight edge of the rear leaf, such as the edge 10 in extension, and attached to the leaf on both sides, and the multi-ply margin may then be cut away to form a tab of the size and shape desired. For some purposes, however, the projecting tab is not essential or desirable, and it may also be preferred to form the reinforcement of two separate strips dispensing with the fold line at 11.

In Fig. 1 the reinforcement is lined to illustrate the color pink or red to contrast with the buff color of the untinted manila folder as an illustration of one of the many possible color combinations which may be used as a signal to indicate the subject matter of the file contents. The uses of such color signals will depend largely on the nature of the business in which the folders are utilized and the desired diversity of classification of the subject matter. For instance the color of the folder may indicate a particular classification of subject matter and the color of the reinforcement may relate to a subdivision of that class; or the combinations of colors may be used for other purposes. Names, numerals, or other specific indicia of subject matter may be inscribed upon the tab or margin or affixed thereto by means of a separate slip.

The margin of a folder which is reinforced in the manner herein described is sufficiently stiff and durable to resist the bending stresses to which it is subject by normal handling during use without cracking at the lower edge of the reinforcement, and provides a stout edge or tab which preserves whatever index data may be applied thereto. The adhesively secured reinforcement not only furnishes a triple thickness at the region of handling, but also provides the additional stiffness and strength which is provided by the application of the adhesive between the folder leaf and the respective side flaps of the reinforcement.

When the reinforcing strip is folded over the top edge of the leaf or tab a sharp laminated edge, which is irritating to the touch and which tends to split or crack in use, is obviated. The necessity for sharply scoring and so weakening the fold line 11 is also eliminated, for the folded portion of the reinforcement embraces the upper edge 10 of the body of the tab, which provides a base sufficiently thick to prevent cracking at the fold. Such construction furthermore en-

sures permanent adherence of the strip to the tab at the region adjacent edge 10, as well as elsewhere, and avoids the tendency of the fold to resist the adhesive at this point. Such weakness would exist if, for example, the reinforcement consisted merely in folding over and pasting down an integral flap portion of the folder leaf. The fold line would then tend to crack if not scored, and the springiness of the fold would resist permanent adherence at the region of the fold, with a tendency of the flap to separate from the body of the folder at this locality, thus weakening the tab and resulting in ultimate release of the flap from the face of the folder.

The upper margin of the front leaf 4 preferably overlaps the lower edge 15 of the reinforcing strip and extends nearly but not quite to the upper edge of the rear leaf, so that the top edge of the front leaf will not tend to catch beneath the edge 15 and yet the rear leaf 5 will project a little beyond the front leaf 4 to facilitate the opening of the folder.

I claim:

1. A folder comprising a folded sheet having front and rear leaves, and a reinforcement adhesively applied upon both sides of the exposed edge of one of said leaves, whereby the said exposed edge is a three-ply composite structure, the reinforcement on one side of said sheet extending downwardly below the bottom edge of the reinforcement on the other side of the sheet.

2. A folder comprising a folded sheet having front and rear leaves, and a reinforcement adhesively applied upon both sides of the exposed edge of one of said leaves, the thickness of each side portion of the reinforcement being approximately the same as the thickness of the sheet whereby the said exposed edge has a thickness substantially three times as great as the sheet, the reinforcement extending outwardly to the lateral margins of the sheet on each side thereof and the reinforcement on one side of said sheet extending downwardly below the bottom edge of the reinforcement on the other side of the sheet.

3. A folder comprising a folded sheet having an integral projecting tab at one exposed margin, and a separate reinforcing strip of sheet material having approximately the same thickness as the sheet folded over the outer edge of said tab and having side flaps extending downwardly over said sheet margin and outwardly to the lateral margins of the sheet, said strip being adhesively secured to said tab and sheet upon the opposite faces thereof and the flap on one side of the sheet extending downwardly below the bottom edge of the flap on the other side of the sheet.

4. A folder comprising a folded sheet having front and rear leaves, and a reinforcement applied upon the exposed edge of one of said

leaves, said reinforcement having a color contrasting with the color of the folder sheet.

5. A folder comprising a folded sheet having front and rear leaves, and a reinforcement applied on both sides of the exposed edge of one of said leaves, said reinforcement having a color contrasting with the color of the folder sheet, whereby said contrasting colors are visible from both sides of the folder.

10. 6. A folder comprising a folded sheet having front and rear leaves and having an integral projecting tab at the exposed margin of one of said leaves, and a separate reinforcing strip of the same material as said folded sheet folded over the outer edge of said tab and extending downwardly over the adjacent margin of said leaf and outwardly to the edges of the leaf, said strip being adhesively secured to said tab and leaf margin upon the 15 opposite faces thereof, to provide a triple-ply, composite, reinforced margin having a thickness substantially three times as great as that of the body of the leaf.

7. A folder comprising a folded sheet of 25 heavy paper having front and rear leaves and having an integral projecting tab at the exposed margin of one of said leaves, and a reinforcement consisting of a folded strip of the same material as said sheet applied 30 upon said tab and along said margin from one side of the leaf to the opposite side, to provide a triple-ply margin having a thickness substantially three times as great as that of the body of the leaf, said three plies being 35 adhesively united to each other and the outer edge of the tab portion constituting a rounded fold in which the free edge of one of the plies is embraced within the folded material, thereby reducing the tendency of the folded 40 paper to crack or separate during handling.

Signed by me at Boston, Massachusetts,
this 30th day of November, 1926.

ROY H. CHARLTON.
